COLLAPSIBLE DISPLAY BASKET

Harvey Polay, Manhattan Beach, N. Y., assignor
to Badger Cutouts, Inc., Brooklyn, N. Y., a corporation of New York

Application January 28, 1942, Serial No. 428,519

4 Claims. (Cl. 206—44)

This invention relates to improvements in display containers and more specifically to a collapsible display basket in which small articles of merchandise may be conspicuously displayed upon the counter of a store.

Some of the important features of the invention reside in a collapsible cardboard display basket which is collapsible to a flat condition to facilitate compact storage and shipment of the same; which is easy to set up for use by a store-keeper; which is strong when set up to withstand breakage caused by stress to which the basket is subjected when in use; and which is constructed of a minimum amount of stock, thus eliminating waste stock which makes the basket inexpensive of manufacture compared to other collapsible display baskets heretofore produced.

Another feature of the invention is to provide a collapsible display basket in which the same is secured in set up position by hook members folded from side wall flaps formed integral with the bottom wall of the basket, the hook members interlocking with the walls of slots provided in opposed corners of the side walls, the said side wall flaps acting to close the open space between the side walls and the bottom wall and to reinforce the side walls against outward stresses applied thereto by articles of merchandise when placed in the basket for display purposes.

Other features of the invention will become apparent as the following specification is read in conjunction with the accompanying drawings, in which:

Figure 1 is a perspective view of the collapsible display basket in set up position for use.

Figure 2 is a vertical transverse sectional view on the line 2—2 of Figure 1.

Figure 3 is a horizontal sectional view on the line 3—3 of Figure 2.

Figure 4 is an enlarged detail horizontal sectional view on the line 4—4 of Figure 1.

Figure 5 is a detail vertical sectional view on the line 5—5 of Figure 4.

Figure 6 is a detail outside perspective view illustrating the interlocking connection between the bottom and side wall structures.

Figure 7 is a perspective view of the display basket in collapsed position.

Figure 8 is a plan view of the main blank from which the basket is constructed.

Figure 9 is a plan view of the blank from which the front wall is constructed.

Referring to the drawings by reference characters, the numeral 10 designates the collapsible display basket in its entirety, and which is con-

structed of a main blank of cardboard A (Figure 8) and a supplementary blank of cardboard B (Figure 9). Whereas the blanks A and B are separate for economy in manufacture due to a minimum of waste stock in cutting the blanks, the blanks A and B may be of one integral piece if so desired as will be appreciated hereinafter. Also, while the material from which the basket is constructed is referred to as "cardboard," the same may be made of heavy paper stock, corrugated board, or other materials having like characteristics.

The blank A includes a hexagonal bottom wall panel 11, the front edge 12 being an edge of the blank. The other five edges of the bottom wall panel 11 have portions of the blank integral therewith. Front side wall flaps 13—13 are attached to the bottom wall panel 11 along hinge scores 14—14, the inner end edges of the flaps 13 being at right angle to the respective hinge scores 14—14. Rear side wall flaps 15—15 similar to the flaps 13—13 are connected to the rear side edges of the bottom wall panel along hinge scores 16—16. The rear side edge of the bottom wall panel 11 has a rear wall panel 17 connected thereto along a hinge score 18 which is parallel to the free front edge 12.

The adjacent inner ends of the pairs of flaps 13 and 15 define a V and said ends are connected within the V by a substantially V shaped web 19, the same being scored at their joinder with the flaps on the score lines 20—20. The mid portion of the web 19 is scored transversely on the line 21 to divide the web into two like sections foldable upon themselves when the blank is folded to provide a downturned hook locking tongue T as clearly illustrated in Figures 4 and 5. The web 19 is cut so that the bill portion of the tongue extends in spaced relation to the adjacent inner end edges of the flaps 13 and 15. The flaps 13 and 15 extend the full length of the respective side edges of the bottom wall panel 11 but their free outer or top edges are shortened at the outer ends and the flaps provide the desired reinforcement as will be appreciated hereafter.

Integral with the ends of the rear wall 17 are rear side wall panels 22—22, the said rear side wall panels being connected to the rear wall panel along hinge scores 23—23, the inner ends of which meet at the corners of the scores 16—16 and 18. The rear side wall panels are of a length equal to the rear side edges of the bottom wall panel defined by the hinge scores 16—16, and integral with and connected to the front ends 55 of the rear side wall panels 22—22 along hinge

scores 24—24 are attaching flaps 25—25. The rear side wall panels 22—22 are slit as at 26—26 adjacent the flaps 25—25, the ends of said slits meeting the score lines 24—24 so that the portions of the panels 22—22 defined by the slits and fold lines 24—24 will fold with the flaps 25—25 when the blank is folded so as to provide slots S—S for receiving the respective locking tongues T—T. The slits 26—26 converge downwardly to provide wedge or cam edges 27 for the tongues T as they are inserted into the respective slots S. A display panel 28 is integral with and extends upwardly from the rear wall 17 and if desired, the display panel may be wider than that shown to extend upwardly from the rear side wall panels 22—22. Advertising indicia may be printed upon the front side of the display panel and which would be significant to the particular articles of merchandise to be displayed in the basket 10.

The bottom wall 16 is provided with a medial hinge score 29 which is parallel to the score 18 and free edge 12 to divide the bottom wall into two identical bottom wall sections 16a and 16b and which sections fold inwardly upon themselves when the basket is collapsed and which assume a common plane when the basket is in set up position for use.

The supplementary blank B is substantially rectangular and elongated in plan and is of a length slightly greater than the combined widths of three side edges of the hexagonal shaped bottom wall 16. The blank B is provided with two spaced vertical hinge scores 30—30 respectively disposed equal distances from the vertical center of the blank and which divides the blank into an intermediate front wall panel 31 of a width equal to the length of the edge 12 of the bottom wall, and front side wall panels 32—32 which are slightly longer than the sides of the bottom wall defined by the hinge scores 14—14. An attaching flap 34 is integral with the lower edge of the front wall panel 31 along a hinge score 33. The attaching flap 34 extends substantially the width of the front wall panel 31.

To assemble and connect the two blank sections A and B to form the basket 10, the blank A is folded first. The rear side wall flaps 13—13 and 15—15 are folded inwardly to vertical position on the respective hinge scores 14—14 and 16—16 which causes the V-shaped webs 19—19 to fold outwardly on scores 21—21 to form the hook shaped tongues T—T. The rear side walls 22 are folded forwardly on the hinge scores 23—23 to a position against the rear side wall flaps 15—15, after which the attaching flaps 25—25 are folded outwardly to a position at substantially right angle to the panels 22—22 which causes the cut outs formed by the slits 26—26 to pop out and assume the same plane as the flaps 25—25 but which extend inwardly. The blank B is now folded inwardly on the hinge scores 30—30, and the flap 34 is folded inwardly on the hinge score 33 to a position at right angle to the front wall panel 31. The folded blank B is fitted to the open front side of the folded blank A with the flap 34 underlying the front of the bottom wall section 16a and with the front wall panel aligned with the free edge 12 thereof. Metal stitches or staples 35 pass through the flap 34 and bottom wall section 16a, but if found expedient, the flap 34 may be adhesively secured to the underside of the bottom wall section. The front side wall panels 32—32 fit against the respective up-folded flaps 13—13 and being wider

than the length of the front side edges of the bottom wall defined by the hinge scores 14—14, the free ends of the panels 32—32 lap the outwardly folded attaching flaps 25—25 and are secured thereto by metal stitching or staples 36, although the parts may be adhesively or otherwise secured if so desired. The blanks A and B have now been folded and secured and when in the position just described and as illustrated in Figures 1 to 6, the basket is in open position and is secured in such position by inserting the hook tongues T—T in the respective opposed slots S—S whereupon the side and bottom wall structures are held against movement to collapsed position. However, to collapse the set up basket 10, the operator first grasps the two inner corners of the adjacent pairs of flaps 13—13 and pulls upwardly thereon, thus causing the tongues T—T to be disengaged from the slots S, whereupon, the bottom wall sections 16a and 16b fold upwardly on the hinge scores 23 and 18 and upon themselves on the hinge score 29. After the initial manipulation just described, the side wall structure consisting of the side wall panels 31 and 32—32 have been folded toward the corresponding side wall panels 22—22 and 17, whereupon, the basket assumes a substantially flat collapsed appearance as shown in Figure 7, and at which time the flaps 13—13 fold flat against the bottom wall section 16a and the flaps 15—15 likewise fold flat against the bottom wall section 16b.

To set up the basket from its collapsed position, the operator may grasp the free ends of the front side wall panels 32—32 and the flaps 25—25 to which they are secured and push inwardly thereon, which causes the side wall structure to open up and the bottom wall sections 16a and 16b to unfold and move downwardly. This causes the hook tongues T—T to enter the slots S—S but should the tongues not freely enter the slots, the operator may impart a slight downward pressure upon the meeting top corners of the flaps 13—15, whereupon the tongues will wedgingly engage the wedge edges 27 of the said slots and be securely held against accidental disengagement. The stitched ends of the front side wall panels 32—32 act to conceal the outwardly extending ends of the tongues T—T when the basket is viewed from the front.

While I have shown and described a collapsible basket 10 in which the side walls are vertical, I wish it to be understood that the invention set forth herein may be embodied in a collapsible basket in which the side walls are upwardly and outwardly inclined and which shape is common in display baskets heretofore produced. Such shape basket may be constructed by cutting and scoring the side walls at angles other than right angles. Also, the basket 10 may be constructed from a single blank of cardboard material, wherein the bottom edge of the front wall panel would be integral with the edge 12 of the bottom wall and connected thereto along a hinge score equivalent to the hinge score 33. Further modifications in structure and design as come within the scope of the appended claims may be resorted to if desired without departing from the spirit of the invention herein shown and described.

Having thus described the invention, what I claim as new and desire to secure by Letters Patent of the United States, is:

1. A collapsible cardboard display basket comprising a hexagonal bottom wall, a hexagonal side wall structure consisting of pairs of opposed

articulated side walls, two opposed edges of the bottom wall being hingedly connected to a pair of opposed side walls, upwardly extending pairs of flaps hinged to the other edges of the bottom wall along the width thereof to close the joints between the said edges and adjacent complementary side walls, hook tongues provided at and integral with the meeting ends of the respective pairs of flaps, slots provided in adjacent side walls through which said tongues extend and lockingly engage, and a medial hinge score provided in said bottom wall extending from the meeting corners of one pair of flaps to the meeting corners of the other pair of flaps to facilitate the inward folding of the bottom wall and flattening of the side wall structure when the tongues are disengaged from the slots to effect a flat compact collapsing of the display basket.

2. A collapsible cardboard display basket comprising a collapsible side wall structure composed of six side walls articulated together, a hexagonal bottom wall having two of its side edges hingedly connected to two opposed side walls, upwardly extending flaps respectively hingedly connected to the other side edges of the bottom wall and defining pairs of adjacent flaps for respectively reinforcing those side walls not hinged to the bottom wall, a folded hook tongue integral with the adjacent ends of each pair of flaps, a slot provided in the side wall structure adjacent each hook tongue to receive and interlock with the same, and a medial hinge score extending across the bottom wall parallel to the axis of the pivotal movement of the hinge connections between the bottom wall and the two opposed side walls.

3. A collapsible cardboard display container comprising a plurality of pairs of opposed side walls hingedly connected together at their ends

to provide a continuous collapsible side wall structure, a one-piece bottom wall hingedly connected to a pair of opposed side walls, a medial hinge score extending across said bottom wall and being parallel to the pivotal axes of the hinge connections between said bottom and opposed side walls and dividing the bottom wall into two like upwardly foldable bottom wall sections, upwardly extending flaps hingedly connected to the other sides of the bottom wall, hook tongues integral with adjacent meeting ends of said flaps and projecting therefrom, and slots provided in adjacent side walls for interlockingly receiving said tongues.

4. A collapsible cardboard display container comprising a plurality of pairs of opposed side walls hingedly connected together at their ends to provide a continuous collapsible side wall structure, a bottom wall having opposed sides conforming to the number of side walls and being hingedly connected to a pair of opposed side walls, a medial hinge score extending across said bottom wall from opposed pairs of meeting corner edges thereof and being parallel to the pivotal axes of the hinge connections between said bottom wall and opposed side walls and dividing the bottom wall into two like upwardly foldable bottom wall sections, pairs of adjacent upwardly extending flaps hingedly connected to the other sides of the bottom wall, a normally V-shaped web connecting the adjacent meeting ends of the pairs of flaps, said web being transversely scored at its mid portion and folded thereon upon itself to provide a hook tongue projecting from the meeting ends of the flaps, those side walls adjacent the meeting ends of said flaps having slots therein for interlockingly receiving the respective tongues.

HARVEY POLAY.
